UNITED STATES PATENT OFFICE

JEAN LAVERGNE, OF PARIS, FRANCE, ASSIGNOR TO RENÉ FOREST, OF PARIS, FRANCE
MECHANICAL DEVICE FOR THE SUPPLY OF EXPLOSIBLE GAS TO INTERNAL-
COMBUSTION ENGINES

Application filed April 18, 1927, Serial No. 184,736, and in France April 24, 1926.

It is observed that in engines employing carburetted gas or air, the admission of the power fluid to the cylinders is effected by the piston during the suction stroke.

5 This suction produces in the cylinder a pressure which is below atmospheric pressure, and this causes a circulation of the fluid through the carburetter, the conduits and the valves, so as to fill up the vacuum 10 which is set up by the downward stroke of the piston.

For this reason, the pressure of the gas drawn into the cylinder is equal to the atmospheric pressure less the pressure represented by the flow of the fluid through the carburetter, conduits and valves.

15 This loss of pressure increases with the speed of the engine. In this manner the power couple of the engine will decrease, 20 i. e. the weight of the gas admitted, per revolution of the engine, will diminish progressively according as the speed increases.

25 My invention has for its object to mechanically compensate for such losses of pressure so as to obtain, irrespectively of the speed, a constant weight of gas in the cylinders at each revolution of the engine.

The said invention is disclosed in the following description with reference to the appended drawings, wherein:

30 Fig. 1 is a general view showing the feeding device mounted upon the engine.

Fig. 2 is a sectional view of the injector.

In Fig. 1, 1 is the engine, 2 the carburetter 35 and 3 a mechanically operated compressor; 4 is the injector; 5 and 6 are respectively the suction and delivery conduits of the compressor 3; 7 is the feeding conduit for the engine.

40 The injector 4 which is shown in section in Fig. 2, consists of the central nozzle 8, the intermediary divergent element 9 and the main divergent conduit 10. 11 is the suction chamber of the injector.

45 The operation is as follows:

A certain portion of the gas from the carburetter 2, which will be termed "inducing gas," is drawn through the conduit 5 by the compressor 3, it being compressed to 50 a sufficient degree and then discharged

through the conduit 6 into the nozzle 8. Due to the flow of the fluid through the said nozzle, there will be produced a vacuum in the chamber 11 depending upon the speed of this flow.

55 A second portion of gas from the carburetter 2, which will be termed "induced gas" will now fill up the vacuum in the chamber 11, and the whole product, consisting of the "inducing" and the "induced" gas, is discharged through the main divergent conduit 10 which is connected with the beginning 60 of the feeding conduit of the engine 1.

In the example cited, a single carburetor 2 is used which supplies at the same time the inducing gas and the induced gas. However, according to the size of the motor, the inducing gas could be supplied by separate carburetors. In this case the carburetor 65 supplying the inducing gas is to be connected directly with the conduit 5, the communication of which is interrupted with the carburetor while the gas of the carburetor 2 or the induced gas is drawn by the pressure caused by the gas at its leaving the nozzle 8. It is evident that instead of the carburetor 2 a number of carburetors could be used so as to supply the induced gas.

70 Since the compression is adiabatic, the increased temperature of the "inducing" gas will further the homogeneity of the carburetted mixture, and the energetic stirring caused by the injector will produce the phenomenon of turbulence which increases 75 the propagation of the explosive wave.

Claims:

1. A device of the kind described comprising a carburetor, an injector arranged in the feed conduit, a compressor having its suction conduit connected with the carburetor and its delivery conduit connected with the injector, a chamber surrounding the feed injector, a conduit connecting the said chamber with the carburetor.

2. A device of the kind described comprising a carburetor, an injector in the feed conduit, a divergent intermediary Venturi tube and a divergent principal Venturi tube, a compressor having its suction conduit con-
